BOAT SLIP

Linn W. Coffey, 6105 La Jolla Scenic Drive,
La Jolla, Calif.

Filed Apr. 9, 1963, Ser. No. 74,367

Term of patent 14 years

(Cl. D71—1)

FIG.1.

FIG.2.

FIG.3.

FIG.4.

FIGURE 1 is a perspective view of a boat slip showing my new design;

FIGURE 2 is a top elevational view thereof;

FIGURE 3 is a side elevational view thereof; and
FIGURE 4 is a front elevational view thereof.

I claim:

The ornamental design for a boat slip, substantially as shown.
